Oakley, Cincinnati, Ohio, a corporation of Ohio

Application May 21, 1940, Serial No. 336,371

11 Claims. (Cl. 77—28)

This invention relates to portable machine tools and more particularly concerns improvements in a drilling machine that may be wheeled from place to place about the workpiece, leveled and locked in the desired location, and the tool spindle accurately located and aligned for the performance of the immediate tooling operation upon the piece.

A primary aim of the invention is to provide the user with a machine having steadiness and rigidity when brought into working relation with the workpiece with the additional advantage of power and capacity far exceeding the capacity of conventional portable hand tools. Still a further object of the invention is to enable the user to effect a plurality of tooling operations, such as drilling, boring, reaming and analogous types of operations, at various locations vertically and horizontally in the workpiece with but a single transportation operation of the machine as a whole. That is to say, to enable the user to wheel the machine to a position adjacent the workpiece and then level it (with respect to the floor or the plane of the workpiece to be operated upon) and thereafter adjust the tool spindle vertically, horizontally, and/or angularly as may be desired properly to position the tool with the workpiece. Subsequent operations upon the same piece may be performed in rapid succession by readjusting certain of the elements of the machine, on and relative to, the wheeled base of the machine without disturbing the leveled condition of the machine as a whole. By this invention a succession of spaced tooling operations, for example, drilling, may be performed with assurance that the different drilled holes are accurately located and properly related to each other. Errors and difficulties in alignment and location of a tool incident to the use of the conventional portable hand tools whether they are supported entirely by the operator or by a shop crane, are eliminated with a portable yet rigid machine of the present character.

A further aim of the invention is to provide users with a practical efficient tool of generous capacity but compact in design so that it may be moved bodily about the work, and when necessary, placed inside hollow workpieces and operated therein to perform relatively heavy tooling operations that heretofore could not be accomplished except by initially designing the workpiece in several parts, each in a manner capable of being conveniently handled and machined as separate entities on existing machines of the conventional type.

With the aid of this invention the design of parts and structures has been greatly simplified, for now the largest of workpieces may be cast or otherwise fabricated in one piece, and thereafter

accurately machined, not by taking the work to the tool, but by bringing the tool to the work.

The present invention further aims to fill an existing need now present in manufacturing plants throughout the country for a powerful machine intermediate the bench type and the hand ported class and the much larger class of tools that require, and are set up on, permanent bases and foundations. One important feature 10 of the instant invention in portable machines is that the present machine is designed and adapted to perform tooling operations upon large workpieces that heretofore required massive, elaborate, and expensive equipment to perform 15 the most simple tooling operation. For example, a given casting such as an automobile die block, planer bed or punch press base, may and frequently does weigh 10, 15 or 20 tons, and the problem and cost of moving such a piece to a 20 fixed machine tool, is in the first instance, an expensive undertaking. Secondly, the machine which is to perform the operation must of necessity be exceptionally large and strong in order to accommodate the large heavy workpieces. In 25 consequence, factory overhead and operating costs are disproportionately high for the actual machining done with existing methods.

With the aid of this invention, however, the heavy workpiece need be handled only once, i. e., blocked up and/or leveled, and one or more machines of the character hereinafter more fully explained wheeled to the work, leveled and locked in the position required for the tooling operation. Several machines constructed in accordance with this invention may operate simultaneously upon a single workpiece and in this way expensive and permanently located machinery is released for other duty, or eliminated entirely, and the costs, delays and dangers incident to 40 shifting heavy work from place to place about the manufacturing plant is likewise eliminated.

In its more specific aspects the invention also aims to provide a drilling machine in which the drill spindle is arranged to rotate on a horizontal axis, which axis may be raised or lowered, shifted laterally relative to any given point upon the wheeled base of the machine, or swung angularly about a vertical axis that lies preferably in a plane containing the horizontal axis of the 45 spindle. This latter feature enables the user to place the machine inside of circular or open workpieces in which it may be desired to drill one or a series of holes radiating from a common center and lying in the same or different horizontal planes. The several transverse adjustments 50 embodied in this machine, renders the machine exceedingly flexible and adaptable for a great many tooling operations that have heretofore presented serious difficulties to the designer and manufacturer.

Still a further objective of the invention is to provide a machine in which the user is given a high degree of sureness and fixedness in the making of adjustments in spindle location, both vertically and laterally, relative to the pre-leveled base of the machine to the end that only one attendant is required to operate the machine, thereby dispensing with the need for a staff of operators as are now required to operate crane supported or hand supported power tools.

In attaining the foregoing objectives and others that will become apparent from the following, it is now proposed to arrange a horizontally disposed tool spindle for translation upon an upstanding rotatable column with the axis of the spindle passing through the column axis. The immediate support or housing for the spindle also carries a simplified train of drive gearing, drive motor, and feed mechanism by which the spindle may be rotated at various speeds and fed axially to and from the work.

The revolvable tool supporting column is mounted upon a stub column which in turn is slidably mounted on slideways formed upon a wheeled main support or base member. By virtue of this improved arrangement and relation of elements, the spindle may be raised or lowered, swung angularly completely about the column axis, or shifted laterally from side to side thereby to locate the spindle at the exact point required for the operation without disturbing the main base which is initially leveled and locked in position adjacent the workpiece. For the more heavy tooling operations, wherein the reacting forces may have a tendency to push the tool away from the workpiece, means are provided, which for convenience may be in the form of a chain, for tying the tool head of the machine directly to the workpiece. The chain performs no tool feeding function but is arranged to exert its tensile force substantially in alignment with the tool spindle so that there is no separation or springing of the parts.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which—

Figure 1 is a side elevational view of the complete machine embodying principles of this invention.

Fig. 2 is another side elevational view of the machine looking toward the spindle end.

Fig. 3 is a plan view of the machine.

Fig. 4 is a side view of the machine with portions thereof shown in section better to illustrate certain features of the construction.

Fig. 5 is a sectional view of the column traversing mechanism.

Fig. 6 is a sectional view through a portion of the spindle drive train and gear shifting mechanism.

Fig. 7 is a detail view of a preferred form of spindle start, stop, and reversing control.

Fig. 8 is a rear view of the machine in working relation with a workpiece.

Fig. 9 is a fragmentary detail view of a modified form of head clamping construction.

With reference more particularly to Figs. 1 to 4, the machine is supported upon a wheeled base member 10 which is nearly square in plan view and has its hollow interior adequately ribbed and reinforced against flexing. The two rear corners of the base have a pair of relatively wide-flanged wheels 11 journaled therein which support that end of the machine a clearing distance from the floor. At the opposite end of the base and midway its sides, a third wheel 12 is journaled in the arm of a bifurcated shaft 13 which is revolvable about a vertical axis in a housing 14 secured to the main base. The upper end of the shaft 13 has secured thereto a bracket 15 to which a draw handle 16 is pivoted. When the machine is being wheeled about, the handle 16 occupies a position about as illustrated in Fig. 2, and is used also as a steering medium for the forward wheel 12. When not in use as a draft bar, the handle 16 may be latched in an upright position as illustrated in dotted lines. The three wheels accordingly provide a three point contact with the floor in a manner promoting easy maneuverability of the machine in close quarters and during the act of transporting the machine about the shop. The forward single caster 12, being mounted as to turn through a complete circle, the machine may be turned end for end in a narrow compass and otherwise stationed in practically any position desired relative to a workpiece of complex design or contour.

After the machine has been wheeled to the required tooling station, the three point contact with the floor, effected by wheels 11 and 12, is replaced by a four point contact established by the manual operation of jacking devices, each of which includes a locking screw 17 located at each corner of the base 10. Inasmuch as the locking screws 17 are all alike, the description will be confined to the one illustrated in section on Fig. 4.

Each locking screw has a threaded connection 18 with the main base and carries at its lower end an enlarged foot member 19 mounted relatively loosely thereon. The connection between the foot 19 and the shaft 17 may be in the form of a ball and socket type of joint 20, or any other type that will allow the foot to adjust itself to irregularities in the floor. The floor side of each foot 19 is roughened, as at 21, to insure a firm and non-skidding engagement of the machine with the floor when the handles 22 are operated to lower the locking feet and thus raising the wheels of the machine off the floor.

Each of the corner jacking devices (17-22) are independently adjustable vertically so that the main base 10 of the machine may be leveled notwithstanding that the floor may slant or contain severe irregularities in surface contour at the region where it may be desired to use the machine. To assist the operator in leveling the machine (whereby the tool spindle is also leveled) a pair of water levels 23, 24 are inserted in the base, preferably flush with the surface 10a thereof. One of the levels serves to indicate trueness longitudinally and the other level indicates trueness in the transverse direction or crosswise the machine. When the bubble in each level comes to zero position by the appropriate movement of the corner jacks, the machine as a whole is leveled and the tool spindle may be swung in a complete circle without error.

Swinging of the tool spindle angularly is effected in the present embodiment of the invention by revolvably mounting the main supporting column 25 upon a normally fixed stub column 26. The stub column projects upwardly inside of the column 25 from a base portion 27 thereof. The base portion of the stub column has its upper and lower surfaces 28 and 29 finished to provide bearing surfaces, the upper surface 28 being annular to support thereon the lower end surface 30 of the revolvable cylindrical column 25, and its under surface rectangular so as to be capable of translation. Radial thrust bearings 31 and 32 located respectively at the top and bottom of the stub column 26 support and guide the outer column 25 thereon.

At its extreme lower end, the outer column is formed with a projecting annular flange 33 which is overlaid by two guide and clamping straps 34 and 35. Each strap has a heel portion 36 that engages the base element 27 and acts as a fulcrum, and a toe portion 37 that overlays the annular flange 33, and between the toe and heel portions of the strap, clamp screws 38 exert their pressure. Preferably both clamp straps are pulled down against the column flange with a moderate pressure sufficient to prevent any separation between the annular thrust bearing surfaces 28 and 30, and are locked in position by locking means 38a. The pressure exerted by the clamp straps in addition to the normal weight of the column and parts supported thereby is not sufficient to prevent adjustment of the column angularly on the bearing surfaces and, to effect a firm clamping of the column in any preselected angular position desired, a lever operated clamp means 39 is provided.

The function of the lever operated means is merely to increase the clamping pressure exerted, by at least one of the clamp straps, to the point of clamping of the column flange 33 firmly against rotation. One or more clamping levers may be provided, but in the event that only one is used, it should be located preferably in that quadrant of the column flange that tends to lift away from the bearing surface 28 during a tooling operation. Fig. 4 of the drawings illustrates the preferred location of the clamp with respect to the tool end of the spindle for the great majority of tooling operations that may be performed with a portable machine of this particular design.

The lower bearing surfaces 29 of the stub column are at least two in number and lie at either side of the column axis. Complementary square guideways 40 are provided by the main base and extend longitudinally thereof (Figs. 2 and 3). The guideways 40 are preferably located slightly above the general plane of the top of the base and provide angularly disposed bearing surfaces 41a, 41b, 41c, 41d for supporting and guiding the complementary surfaces of the stub column slide member 26, 27. Suitable straps 41 and an adjustable gib 41e are provided for establishing and maintaining a close fitting relation of the guides. The fitting of these elements are, as explained above in connection with the rotatable column, not too tight as to prevent movement of the column slide along the ways of the base, but sufficiently tight to prevent any lateral separation between any of the bearing surfaces during a tooling operation.

The purpose of the above described type of column mounting is to enable the user to swing the tool spindle to any angular position as the requirements of the work demand and also to trans-

late the spindle laterally along the ways of the base to new positions without disturbing the previously leveled condition of the base. To facilitate the lateral shifting of the spindle along the base a rack and pinion mechanism 42, 43 operated through a worm and worm wheel 44, 45 is provided. This type of translating mechanism affords not only a powerful drive but a drive that is self-locking, i. e., the machine cannot be moved along the ways of the base unless the handle 46 of the worm drive is manually operated. Auxiliary devices for clamping the column slide to the base are not essential, although if one desires, a clamp constituted along the lines of the column clamp means 39, previously explained, may easily be provided.

The revolvable column 25 is machined cylindrically throughout the major portion of its height and supports thereon, for vertical movement, a tool head 50. The girdle portion 51 of the tool head extends completely around the column and is split along one side at 52 (Figs. 3 and 4) so that a close sliding fit between the head and column may be obtained by the adjusting screws 53. Relative angular movement between the tool head and its supporting column is prevented by the provision of a vertically extending keyway 25a in the column which has fitted thereto a key secured in fixed relation to the inner surface of the sliding tool head. For reasons later to be explained, the split girdle and screws 53 do not function as a head clamping means. The clamping of the head in vertically adjusted position is effected in this instance by means substantially separate from the column and split girdle portion of the head.

As illustrated more clearly in Figs. 1, 2, and 3, the column cap 54 supports a depending shaft 55 which passes to the outside of the girdle portion proper of the head and through a split wing 56 carried by the head, preferably at the upper region thereof. The split 56a extends into the shaft receiving bore in the wing 56 but not to the inner column engaging surface of the girdle. A draw bolt form of clamp, operated through a hand lever 57 is provided for pinching the two parts of the split wing firmly upon the shaft 55. In this way the adjustable head may be clamped in position without imparting or transmitting any of the clamping force to the split tool head per se or to the hollow and longitudinally divided column 25.

According to the head clamping structure illustrated in Fig. 9, which may be preferred by some users, the head girdle portion is split on the operator's side of the machine, and a clamping is effected in by impinging the girdle portion partly on the column and partly on the cap supported rod 55a. In this embodiment of clamp, a non-rotatable but axially shiftable stud 53a passes through the wings of the girdle and carries at one end a manually operable nut in the form of a lever 57a, and at its other end, a set of adjustable check nuts 57b. Underlying the check nuts, a rock lever 57c straddles the drawbolt and extends to opposite sides thereof. One end of the rock lever engages a fixed button 57d set into the head girdle, and the opposite end of the lever engages an axially movable pin 57e, also mounted in the head girdle. The pin 57e is, however, mounted in a bore slightly offset with respect to the axis of the cap supported rod 55a, and carries at its inner end a wedge portion 57f of smaller diameter, to prevent binding in the bore, that engages directly with the rod 55a.

With this type of clamp, a movement of the hand lever 57^a to a clamping position exerts an equalizing clamping pressure of the head girdle on the column 25 as well as on the rod 53^a, neither element receiving the full effect of the clamping pressure, but both sharing the forces jointly. As a consequence, the inner surface of the girdle portion of the head is caused to be brought into intimate engagement with the column surface thereby increasing the rigidity throughout, and the cooperating wedge and shaft members with their localized but intense clamping effect, again serves as the primary head supporting and clamping medium.

When the head clamp is operated to the released position, the head may be raised or lowered on the column by the hand operated screw and nut mechanism illustrated in Figs. 1, 3, and 4. This mechanism includes a normally non-rotatable screw shaft 58, a rotatable nut 59 journaled in the tool head, a hand wheel 60 and gearing 61, 62 ratioed to provide approximately $\frac{1}{4}$ " vertical adjustment for each complete turn of the hand wheel 60.

Referring more particularly to Figs. 1, 3 and 4, the mass of the tool head is apportioned to opposite sides of the supporting column, the tooling side supporting the spindle drive motor 63 and feed mechanism 64, and the opposite side supporting the speed change gear mechanism 65 and the head elevating mechanism 58-62. The substantially balanced distribution of the weight of the tool head at opposite sides of the central support 25 promotes easy translation of the head along the column, without girdle cramping or column deflection effects.

The tool holding spindle 66 is rotatably and translatable journaled in the tool head 50 and passes from one side of the head to the other through the axis of the rotatable column. By arranging the spindle and column axes to intersect in the same plane, strain on the head clamp is relieved, the possibility of drill breakage eliminated and it is possible to drill a succession of holes, all radiating from a common center, without repeatedly readjusting the pivotal axis. By this improved construction there is no one sided thrust on the tool head, column, etc. as would be occasioned if the tool spindle was located offset and at a tangent to its main support.

The above objectives have been attained by the present invention by forming oppositely disposed, longitudinally, extending slots 67 in the cylindrical column 25, each of which stops short of the upper and lower ends of the column leaving a substantial portion 67^a and 67^b extending inwardly from each end of the column, integral and unbroken for increased column strength. The column is further strengthened by solid contiguous segment portions 67^c that extend longitudinally along each side of each of the slots 67 and merge with the inner walls of the column at the upper and lower ends.

The width of the slots comfortably accommodates not only the tool spindle 66, but its translating sleeve 70 by which it is fed to and from the work. The sleeve is translatable mounted in bearings provided in the tool head, and has rack teeth 71 provided along one side thereof adapted to mesh with a pinion 72 on a shaft 73. The shaft 73 extends to the front of the head and has a pair of pivoted handles 74 connected therewith. Manual turning of the handles thus effects

spindle translation in an axial direction toward or away from the workpiece.

Additional spindle translating means are also provided by a hand wheel 75, which through a shaft 76 and a pair of bevel gears 77 is arranged to drive a feed shaft 78 also journaled in the head. The lower end of the feed shaft 78 carries a worm 79 that meshes with a worm wheel 80 loosely mounted on the pinioned shaft 73. A clutch 74^a, arranged for operation by the pivotal movement of levers 74, is interposed between the worm wheel 80 and shaft 73 and gives the operator a choice of methods of effecting spindle translation. Hand wheel 75 affords a slow powerful spindle feed through the worm and clutch mechanism, and levers 74 (when the clutch is disengaged), a more direct and faster rate of spindle traverse. Conventional depth dial and automatic clutch throw-out mechanisms for regulating the travel of the spindle are provided, but as these mechanisms are well known, their description is believed unnecessary.

The tool spindle receives its rotary motions through speed change gearing in a gear box 81 located at the opposite side of the column. This gearing includes a three gear shiftable unit 82 splined to a sleeve 83 that is rotatably journaled in bearings 84 in the gear box. The sleeve 83 is also splined internally and receives the splined end 66^a of the translatable spindle 66. A four gear non-shiftable unit 85 is mounted upon a parallel shaft 86 and receives motion at any one of two different rates from a second sliding two-gear unit 87 splined to a third shaft 88. The first mentioned sliding unit (82) provides three relatively fine changes in speed and the second mentioned gear unit (87) provides two relatively coarse changes in speed, and as the speed change mechanisms are in series, a total of six spindle speed changes may be provided with a minimum of gearing.

As illustrated more clearly in Fig. 6, the speed changes are preferably independently selectable through the medium of separate levers 89 and 90. Lever 89 operates shaft 89^a and shifter fork 89^b for sliding gear unit 87, and lever 90 operates sleeve 90^a and shifter fork 90^b of sliding unit 82. An index plate and pointer mechanism 91 is provided to expedite the selection of the proper spindle speed.

The splined shaft 88 receives its motion from the motor 63 through shaft 92, gear 93 thereon, and gear 94, the latter being mounted upon the shaft 88. Shaft couplings 92^a and 92^b are also provided to facilitate manufacturing and assembling of the several units and to render it a simple matter for the user to substitute different motors and/or gear boxes as his specific demands may dictate.

The motor 63 is preferably reversible, and its start, stop or reverse operation is controlled by a set of switches including reversing switches 101, 102 and a hand operated lever 103. The handle 103 has three positions (forward, stop, and reverse) indicated in dotted lines in Fig. 7, and is provided with a spring actuated roller detent mechanism 104, for resiliently detaining the lever and the switch in a selected position.

After the operator has wheeled the machine to the work location, leveled it and made the necessary adjustments properly to relate the tool spindle to the work, a chain 105, or other convenient form of tie-rod mechanism, may be used to maintain the relation between the tool head and the

workpiece fixed. To that end a sizable recess 106 is provided in the head casting, preferably directly under the spindle, and a removable cross pin 107 inserted therethrough by means of which a positive connection, with respect to the direction of the tooling forces, may be made between the tool head and workpiece. Such a connection, it will be seen, provides additional assurance that the reacting forces of the tooling operation will not spring the machine or any part thereof out of alignment. And in furtherance of this general objective, it is preferred also to position the column axis nearer to one side of the base than the other, such as represented in Fig. 1 so that the forces that may tend to overturn the machine are resisted by the bracing action of the extending larger portions of the base. It has been found that by placing the column axis approximately $\frac{1}{3}$ the distance from one edge of the base and $\frac{2}{3}$ the distance from the other edge, highly satisfactory bracing effects are obtained without materially affecting the symmetry in design.

By so offsetting the column from the center line of the base of the machine, the nose of the tool spindle 66 may be caused to overhang by a slight amount, any part or portion of the wheeled base, whereby the operator may wheel the machine close to a workpiece and use the available axial travel of the spindle to its fullest extent. Moreover, an offset column provides valuable additional space on the base member 10 for tools, jigs, and other equipment that ordinarily will accompany a machine of this character in its travels. And so that such equipment will not roll or be jarred off the machine, the base 10 is formed with a recess 110 of substantial area within which the equipment may be placed.

Fig. 8 of the drawings is representative of a tooling operation and set up for which the present machine is adapted. In this figure, the workpiece W is a heavy casting weighing many tons and in which it is desired to drill a number of holes. For such an operation the workpiece is first shimmed up and leveled on the timbers b and thereafter the portable machine is wheeled alongside. The machine is correspondingly leveled and anchored in the approximate tooling zone by means of the corner jacks 22. The proper tool for the operation is then taken from the tray 110 and fitted in the spindle and, by raising or lowering the self-contained tool head on the column, or by shifting the column laterally, or by swinging the column angularly on its slide, or by a combination of movements, the tool is properly located and aligned with respect to the workpiece. With the various adjusting and clamping features provided in this machine, the operation of locating the tool relative to the work is made relatively a simple matter, compared with the prior methods of shifting heavy and difficult work. After the first tooling operation is performed, the tool is easily relocated at another near by region for another tooling operation without shifting either the work or the machine proper, and where, as in most work, a plurality of holes are to be made within an area of four square feet, the ability to adjust the spindle vertically and laterally to any point within this range, with accuracy and rigidity, is in itself a highly advantageous feature. Tooling operations upon extra large workpieces may be performed with equal ease merely by wheeling the machine from one place to another about the work and leveling,

locking and locating the spindle at each change in location as before.

Without further analysis, the foregoing will so fully reveal the gist of this invention that others can by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim 15 as new and desire to secure the following combinations and elements, or equivalents thereof, by Letters Patent of the United States:

1. A drilling machine combining a base member, a slide member translatable mounted upon 20 said base, said slide member having a stub column upstanding therefrom, means for translating said slide member along the base member, a main column member telescoping said stub column and rotatably supported upon said stub column and 25 slide member, said column having a diametral opening therethrough extending longitudinally of the column, a tool head mounted upon and vertically translatable along said main column and rotatable as a unit therewith, said tool head having a portion extending around the column and across the diametral opening in the column on each side of the column adapted to journal a tool spindle, a tool spindle rotatably and translatable journaled on a horizontal axis in said tool head 30 with the axis of said spindle intersecting the axis of rotation of the supporting column member and said tool spindle extending through the column opening, and means for clamping said rotatable column to said slide member and said head to said 35 main column thereby definitely to position the axis of said tool spindle in a preselected vertical position and in a preselected angular position relative to the line of movement of said slide on said base.
2. A portable machine tool combining a base member, manually operable means for removing said base from its engagement with the floor and for leveling same, said means including a series of elevating screws and built-in devices for indicating the leveled condition of the base in two 40 directions; an upstanding tool supporting column supported by said base member; a tool head slidably mounted upon said column for vertical adjustment therealong; a tool spindle journaled in 45 said vertically movable head with its axis normal to and intersecting the axis of said upstanding column and extending through the column, and said column being provided with a diametral opening extending longitudinally of the column 50 for receiving said spindle therethrough in any position of vertical adjustment of the head along the column.
3. A drilling machine combining a base member, a column supporting slide element translatable thereon, manually operable means for elevating said base from its engagement with the floor and for leveling same in elevated position, an upstanding column rotatably mounted on said slide element the axis of said column being normal to the plane of the base and definitely related with said leveling means at all times, a tool head mounted directly upon said column for vertical movement thereon, and a rotatable and translatable tool spindle journaled in said head 55 and extending through the column with the axis 60

of the spindle transverse to and intersecting the axis of said column, said column having a transversely extending opening therein to receive said tool spindle.

4. A machine tool combining a base member, a medially split column member rotatably mounted upon said base member, a tool head mounted for vertical movement along said column member, a tool spindle journaled in said head, said spindle extending through an opening between the walls of said split column, means for adjusting said head along the split column, means independent of the split column for clamping the head in vertically adjusted position thereby definitely to relieve the said split column of the head clamping forces and all deflection or cramping effects incident thereto, and means for rotating the spindle and for translating the spindle axially relative to the column in its vertically adjusted position thereon.

5. A drilling machine combining a divided column member; a tool head movable therealong; said head including a split girdle portion surrounding said divided column and normally positioned on the column with the end portions of the said split girdle approximately 90° angularly removed from the plane of the division of said column, means for clamping the head in adjusted position along the said column, including a supporting element, clamp means carried by the girdle portion of the head operable to impinge directly upon said supporting element and simultaneously to contract the girdle portion of the head closely on said column, and means to operate said clamp means.

6. In a portable machine tool structure adapted to be moved about the floor to a position adjacent the workpiece to be operated upon the combination of a base member, a tool slide translatable therealong, an upstanding column rotatably mounted to said slide; said column having an opening formed in the side thereof; a tool head vertically movable on the column and rotatable bodily therewith, said head being adapted to support a tool spindle on an axis paralleling the general plane of said base and a portion of which is receivable into the opening formed in said column, independently operable means carried by the base and spaced about the margins of said base for accurately leveling the axis of said spindle and the plane of its swing about the column axis at the particular station adjacent the workpiece to be operated upon to which the machine has been moved, means forming part of the machine structure and coacting with last named means for indicating the leveled condition of said spindle when in said particular station adjacent the workpiece, and means for translating said leveled spindle vertically on the column, laterally along the base, or axially of itself without disturbing the leveled condition thereof.

7. A drilling machine combining a base member, a medially split column member mounted upon said base member, a tool head mounted for vertical translation along said split column, a horizontally disposed tool spindle rotatably and translatable journaled in said tool head, said spindle extending through the opening between the walls of said split column and adapted to mount a tool at one end thereof, worm and worm wheel means carried by said tool head and disposed at the tool side of said column for translating said spindle, means for adjusting said tool

head along the split column and for clamping the tool head in vertically adjusted position relative thereto, and means including speed change gearing at the other end of the tool spindle and at the 5 opposite side of said split column for driving the spindle.

8. A machine tool combining a base member, an upstanding tool supporting column supported by said base member, a tool head mounted on said 10 column for vertical movement therealong, a horizontally disposed rotatable and translatable tool spindle journaled in said head, power means carried by and forming a unitary structure with said vertically translatable head for rotating same; means carried by and forming a unitary structure with said vertically translatable head for feeding the spindle axially relative to the head to effect a tooling operation; and additional means engageable with said head at a point substantially aligned with spindle feed means therein for bracing said head and column against the reactionary forces of the tooling operation, including means engageable with the workpiece for maintaining a definite relation between the position of said head and column on the one hand and the position of the workpiece operated upon on the other.

9. A machine tool having in combination an upstanding rotatable column provided with a longitudinally extending opening; a tool head mounted directly on the said rotatable column for translation therealong; a rotatable and axially translatable tool spindle extending through the column and journaled in said tool head at opposite sides of the column with its axis normal to the axis of the upstanding column; spindle rotating means forming a unitary structure with said tool head for rotating the spindle journaled therein; and feed means also carried by the head for translating the spindle axially relative to said head and said spindle drive means.

10. A horizontal drilling machine combining an upstanding column member; a tool head mounted directly on said column, said head having a sleeve portion surrounding said column and said column being provided with a diametral opening therethrough extending axially thereof; a rotatable and axially translatable tool spindle journaled in said head with the axis of the spindle positioned normal to and intersecting the axis of said column, said rotatable and axially translatable spindle extending through the said diametral opening in the column; and means carried by the head member at one side of the column axis for driving said spindle, and means operative at will at the other side of the column axis for translating said spindle.

11. A horizontal drilling machine including an upstanding column, said column having provided therein a diametral opening extending axially; a tool head mounted directly on said column and adapted for movement therealong; a rotatable and axially translatable spindle journaled in said head with the axis of the spindle perpendicular to, and in the plane containing the axis of the upstanding column, said spindle extending into said diametral opening in the column; means carried by the movable tool head for rotating and feeding the tool spindle to perform a tooling operation; and means for shifting the tool head 70 along the column thereby to raise or lower the horizontal position of the axis of said tool spindle to suit work requirements.
